This invention relates generally to techniques for providing increased strength and rigidity to tubular structural members, and more particularly to methods of internally bracing such members to increase their strength and rigidity without adding substantial additional weight thereto, and to provide techniques for forming such bracing members.

UNITED STATES PATENT OFFICE

2,516,020

METHOD OF BRACING TUBES INTERNALLY FOR SPECIFIC USE IN CONSTRUCTING ALUMINUM OR MAGNESIUM LADDERS

Ancil O. Reed, Indianapolis, Ind.

Application December 20, 1946, Serial No. 717,456

1 Claim. (Cl. 29—155)

2

This invention relates to a method or methods for strengthening any tubular structural members and applies specifically to members made from aluminum or magnesium, commonly referred to as aluminum or magnesium tubing.

An object of this invention is to provide a method of strengthening tubular members so that such members may be used to form ladders, flag poles, gang planks, scaffolding and similar types of structures involving the use of tubular members.

The tube is recognized in structural work as the strongest unit per pound of weight that can be used, and is used in the construction of assemblies subject to tremendous stresses such as airplane engine mounts and the articles tested above, and it is believed that the internal bracing embodying the invention will make possible the construction of such assemblies with tubular members of small diameter, but equal to or possessing greater strength than members of greater diameters.

Another object of the invention is to provide a method of strengthening tubular members, that is simple and economical to use and will produce an article far superior to those being used at the present time.

With the above and other objects and advantages in view, the invention consists of the novel details of construction more fully hereinafter described, claimed and illustrated in the accompanying drawings in which:

Figure 1 is a perspective view of one form of internal bracing, embodying the invention;

Figure 2 is a transverse view of another form of internal bracing;

Figure 3 is another form of internal bracing;

Figure 4 is the same;

Figure 5 is the same;

Figure 6 is the same;

Figure 7 is a perspective view of an internal bracing member and

Figure 8 is a view of an additional form of internal bracing.

Referring in detail, and more particularly to the tubular member shown, in all forms of the invention which, being of similar construction in all cases, will be designated by the numeral 10.

In Figure 1 the member 10 which is formed of aluminum or magnesium is of conventional structure, and the invention comprises the method of internally bracing this member to provide a light structure that will be equal in strength to structures made of heavy materials, such as steel and iron or similar materials. In this form of internal

bracing the member 10 is formed of a tube having a longitudinal axis, and the internal bracing consists of a plurality of strips 11 of material, similar to the material of which the member 10 is made, which are bent along their medial line 12 to form inclined portions 13 of similar area. The strips are then placed as shown in Figure 1 with the fasteners 14 in face to face engagement with each other, and the ends are flanged as at 15. The strips are then placed in the member 10, and all parts are secured as a unit by welding, riveting or shrink fitting, by utilizing temperature differential between the parts. Arc welding, spot welding, high frequency welding or other methods depending on the material, may be used.

In Figure 2, the strips 15 have a greater curved central portion 16 with straight portions 17 at each end, and when secured with the member 10, the ends are bent to form flanges 18. In Figure 3, the strips 19 are similar to the strips 15, except that the curved central portions 20 comprise one third of a circle, and the portions 21 are inclined with relation to the portions 20, and the ends of the portions 21 are flanged at 22. Within the circle formed by the portions 20, similar shaped portions 19' are placed, and these strips have central portions 20', inclined portions 21' and flanged ends 22'. In Figure 4, the strips 23 have straight portions 24 and inclined portions 25 with flanged ends 26, and the portions 24, when positioned in the member 10, form a triangle. In Figure 5, the strips 27 assume a triangular shape having three equal sides 28, and the corners of the equilateral triangle are flattened at 29 where they engage the member 10, and the strip 27' is formed similar to the strip 27, having sides 28' of equal length and flattened corners 29', but the triangle formed is of a size to fit within the triangle formed by the portions 28. In Figure 6, strips 19 and 27' are used to form the internal bracing.

In Figure 8, the strips 30 assume a V-shape having sides 31 having flanged ends 32, and the flanged ends in all instances extend in opposite directions from each other to form contact between the strips and member 10.

In Figure 7, a typical strip of metal is shown, which is similar to all strips previously described, but for purposes of illustration, will be designated as 33. Triangular sections 34 are cut from the strips to lighten the weight thereof, and then the sections cut out of the strip form vertical braces 35, horizontal braces 36 and diagonal braces 37. This lightness of weight is achieved without sacrificing strength.

This method of stress distribution by internal

bracing will greatly increase the rigidity of tubular structural members, and will permit smaller diameters and thinner walls of the tubular members with the same or greater strength as unbraced tubes of greater diameter or greater wall thickness or both.

The tubular members can be aluminum, steel, wood, concrete, magnesium, glass, tin, copper, brass or paper, and as formed, each member will sustain a greater bending stress per pound of weight than other types now in use at the present time.

Thus members braced by any one of the forms previously described will support loads which, at present, are applied to tubular members of greater diameter of heavier walls or both.

It is believed that from the foregoing description, the method involving the invention will be clear to those skilled in the art, and it is to be understood that changes may be made in the methods used, provided such changes fall within the spirit of the invention and the scope of the appended claims.

Having thus described the invention, what is claimed as new and desired to be secured by Letters Patent is:

A method of making a structural unit comprising bending strips of suitable metal to form equi-

lateral triangles of different sizes, the apices of the triangles being flattened to form binding surfaces, heating the larger triangle, inserting the smaller triangle within the larger triangle such that the flattened apices of said smaller triangle are located midway the sides of the larger triangle, allowing the larger triangle to cool and contract thereby resulting in a shrink fit between the triangles, heating a tubular member, inserting the joined triangles within the tubular member and allowing said tubular member to cool and contract thereby resulting in a shrink fit between the tubular member and the larger triangle.
